151,003

DESIGN FOR A MILKING MACHINE CLAW

Emanuel Rawson, Chicago, Ill.

Application October 17, 1946, Serial No. 134,010

Term of patent 3½ years

(Cl. D23—1)

To all whom it may concern:

Be it known that I, Emanuel Rawson, a citizen of the United States, residing at Chicago, in the county of Cook and State of Illinois, have invented a new, original, and ornamental Design for a Milking Machine Claw, of which the following is a specification, reference being had to the accompanying drawing, forming a part thereof.

Figure 1 is a top view of a milking machine claw, showing my new design;

Figure 2 is a side view thereof; and

Figure 3 is a bottom view thereof.

I claim:

The ornamental design for a milking machine claw, substantially as shown.

EMANUEL RAWSON.
